UNITED STATES PATENT OFFICE.

GEORGE M. J. MACKAY, OF SCHENECTADY, NEW YORK, ASSIGNOR TO GENERAL ELECTRIC COMPANY, A CORPORATION OF NEW YORK.

INCANDESCENT LAMP.

1,157,995.

Specification of Letters Patent. Patented Oct. 26, 1915.

Application filed September 11, 1914. Serial No. 861,279.

To all whom it may concern:

Be it known that I, GEORGE M. J. MACKAY, a subject of the King of Great Britain, residing at Schenectady, county of 5 Schenectady, State of New York, have invented certain new and useful Improvements in Incandescent Lamps, of which the following is a specification.

The present invention comprises an 10 incandescent lamp having a concentrated light source and particularly useful in focusing devices, such as projectors.

In a lamp embodying my invention the incandescing glower comprises a filament 15 made to assume a compact form by disposing one closely coiled part inside another.

It is one of the features of my invention to proportion the filament to operate at substantially the same temperature through- 20 out.

The accompanying drawings show in Figure 1 in perspective one form of a completed lamp embodying my invention and Fig. 2 is an enlarged detail view of a double helix 25 filament.

My invention is applicable to evacuated as well as gasfilled lamps, but it is of particular utility in the gasfilled type of lamp because of the decreased cooling effect of the 30 gas convection currents on an incandescent body crowded into a relatively small space.

Fig. 1 shows in general outlines a lamp having a concentrated light source and particularly suitable for projector purposes, as 35 in automobiles, motor boats, stereopticons, and the like. The filament or glower 1 comprises two helices connected in series as more clearly shown in Fig. 2. Although I prefer to use a filament of tungsten my invention, of course, is applicable to glowers 40 of other refractory materials. The leads 2, 3 are sealed into a stem 4 of the globe 5 in the usual manner and suitably connected to the lamp base 6. The globe 5 is either evacuated or filled with nitrogen, argon, or other gas inert with respect to the filament, or mixtures of these gases. The gas pressure preferably approximates atmospheric pressure at the operating temperature of the 45 lamp. In a gas filled lamp the filament 1 may be operated at a higher temperature than in a vacuum, preferably at a temperature giving a specific consumption of about one-half watts per candle power or even 50 lower.

Unless special provision is made the inner helix will operate at a higher temperature than the outer due to the fact that it is closely surrounded by the outer helix, receives heat therefrom and cannot lose as 60 much heat by radiation. The turns of the inner spiral should be spaced closely to each other so as to conserve loss of heat by conduction through the gas, but the turns of the outer surrounding helix should be spaced 65 far enough to allow the light from the inner helix to be emitted and will be cooled to a greater extent than the inner helix. To compensate for this inequality in the rate of heat loss of the two helices, the helices 70 are constructed to generate heat at unequal rates, for example, the outer helix is made of correspondingly higher resistance per unit length than the inner helix. As shown in Fig. 2 the outer helix 7 has a smaller diameter than the inner helix 8. For example, a lamp consuming 4.5 amperes at 8 volts may have a filament in which the diameter of the wire constituting the outer helix is about 7 mils and the wire constituting the 75 inner helix is about 8 mils. A greater amount of heat is generated in the outer turns and thus compensates for the greater rate of heat dissipation and causes the filament to operate at a substantially uniform 80 temperature. No fixed rule for proportioning the resistance of the helices can be given as the heat losses depend on many factors.

The terminal wires 9 and 10 are preferably 85 but not necessarily notched or reduced in diameter near the helices to reduce the heat losses by conduction.

What I claim as new and desire to secure by Letters Patent of the United States, is:

1. An incandescent lamp comprising an 95 incandescent filament part of which is surrounded by another part, said inclosed and inclosing parts being proportioned to operate at substantially the same temperature.

2. An incandescent electric lamp, comprising an envelop, and a coiled conductor of refractory material therein, comprising sections located one within the other, the inner section having a lesser resistance per unit length than the outer section. 100

3. An incandescent electric lamp comprising an envelop, a filling of inert gas at relatively considerable pressure therein, and a refractory metal filament located therein comprising helices located one with- 110

in the other, the filament section constituting the inner helix having a greater cross-section than the outer.

4. A concentrated source incandescent lamp, comprising an envelop, a filling of inert gas therein, and a tungsten filament mounted therein comprising at least two sections connected in series, one of said sections being surrounded at least in part by another section, the outermost section having a greater resistance per unit length than the inner section or sections.
5. An incandescent lamp comprising an

envelop, a refractory metal filament mounted therein, said filament comprising a plurality of turns, one part of said filament turns inclosing another part, said filament being constructed to operate at a substantially uniform temperature. 15

In witness whereof, I have hereunto set 20
my hand this 8th day of September, 1914.

GEORGE M. J. MACKAY.
